(57) **CLAIM**

The ornamental design for a vehicle headlight lens, as shown and described.

DESCRIPTION

FIG. 1 is a frontal perspective view of a left vehicle headlight lens attached to a vehicle, no part of the vehicle is claimed;

FIG. 2 is a perspective view of the left vehicle headlight lens;

FIG. 3 is a front elevational view of the left vehicle headlight lens;

FIG. 4 is a top plan view of the left vehicle headlight lens;

FIG. 5 is a bottom plan view of the left vehicle headlight lens;

FIG. 6 is a left side elevational view of the left vehicle headlight lens;

FIG. 7 is a side (45 degrees right of front) view of the left vehicle headlight lens;

FIG. 8 is a front elevational view of a vehicle headlight lens illustrated in FIGS. 1-7, showing a right vehicle headlight lens, with the vehicle shown in broken lines and forming no part of the claimed design;

FIG. 9 is a perspective view of the right vehicle headlight lens;

FIG. 10 is a front elevational view of the right vehicle headlight lens;

FIG. 11 is a top plan view of the right vehicle headlight lens;

FIG. 12 is a bottom plan view of the right vehicle headlight lens;

FIG. 13 is a right side elevational view of the right vehicle headlight lens; and,

FIG. 14 is a side (45 degrees left of front) view of the right vehicle headlight lens.

The phantom lines are not a part of the claimed invention.

1 Claim, 14 Drawing Sheets
